FREDERICK P. PALEN AND WILLIAM BURLINGHAM, OF NEWPORT NEWS, VIRGINIA.

WATER-TUBE BOILER.

1,118,676.

Specification of Letters Patent. Patented Nov. 24, 1914.

Application filed July 6, 1914. Serial No. 849,305.

To all whom it may concern:

Be it known that we, FREDERICK P. PALEN and WILLIAM BURLINGHAM, citizens of the United States, residing at Newport News, 5 in the county of Warwick, State of Virginia, have invented a new and useful Water-Tube Boiler, of which the following is a specification.

Our invention relates to a novel construction of a water tube boiler, wherein we employ an upper steam drum of large diameter, below which, on either side thereof, is a lower drum, said drums being connected by nests of tubes and preferably by upper and 10 lower nests of curved water tubes and an intermediate nest of straight water tubes, there being one or more lower baffle plate or plates inclining upwardly from each of said lower drums, which baffles are collocated in 15 coöperative relation to intermediate baffle plates, which extend downwardly on diverging lines from the upper steam drum toward the lower water drums at a point intermediately of said nests of tubes, whereby a 20 secondary combustion chamber is created in proximity to the bottom of said steam drum so that the products of combustion are perfectly consumed and are directed to the points where the heat units will be most effectively utilized, in order to raise the water 25 in the boiler to the requisite temperature to obtain the requisite circulation between the large steam drum and the lower water drums. It is well known to those skilled in 30 the art that in order to obtain the greatest efficiency from a device of this character, it is essential not only that a thorough combustion take place, but that the heat units must be directed to impinge upon proper 35 portions of the heating surfaces, so that an effective and rapid circulation and consequent steam generation will be attained under all conditions, and by our novel collocation of baffle plates and water tubes, pro- 40 vision is made for causing a complete com- 45 bustion of the gases prior to the egress of the products of combustion to the stack, so that the oxygen admitted above the fire grate properly combines with the products 50 of combustion and effects more perfect and thorough combustion than heretofore. By the employment of the upper diverging baffle plates located intermediately of the 55 nests of tubes and the lower, upwardly con- 60 verging baffle plates, the hot gases are tem- 65 porarily pocketed in the top of the combus- 70

tion chamber below the steam drum, so that the surfaces of the lower nests of water tubes are acted on, not only by the first combustion which takes place in proximity to 60 the grate, but also by the secondary combustion or recombustion which takes place in the upper portion of the combustion chamber which is accompanied by the resultant intense heat, which concentrates in the 65 upper part of the combustion chamber in proximity to the lower portion of the steam drum and the lower nests of water tubes connected thereto. Consequently, it follows that in our novel construction, intense heat 70 is applied to the inner or lower nests of water tubes, so that a rapid upward circulation is created, said circulation being in a downward direction through the upper nests of tubes, whereby a circulation is created of 75 such character that there will be no lodgment of scale in the water tubes, as we have found from a series of practical experiments.

By our novel collocation of baffle plates in 80 a boiler of the character described, any un- consumed products of combustion have am- ple time to commingle with the oxygen in- 85 troduced into the combustion chamber, so that a complete combustion takes place owing to the reverberatory action in the upper combustion chamber prior to the action of the suction of the draft carrying off the con- sumed gases. As a result of our novel con- 90 struction and collocation of water tubes and baffle plates, the lower nests of tubes are 95 initially very highly heated, which causes a rapid upper circulation, which heat is lost very rapidly as the products of combustion pass around and above the upper diverging baffle plates, the result of which is to greatly increase the circulation and steaming ca- 100 pacity of the boiler so that all the heat units are utilized to a maximum extent.

To the above ends, our invention consists 100 of a novel construction of a water tube boiler, comprising a novel arrangement and collocation of upper steam drums, lower water drums and inclined water tubes in con- 105 junction with a novel arrangement of baffle plates coacting therewith.

It further consists of other novel features of construction, all as will be hereinafter fully set forth.

For the purpose of illustrating our inven- 110 tion, we have shown in the accompanying drawings, one form thereof, which is at pres-

ent preferred by us, since the same will give in practice satisfactory and reliable results, although it is to be understood that the various instrumentalities of which our invention 5 consists can be variously arranged and organized and that our invention is not limited to the precise arrangement and organization of these instrumentalities as herein shown and described.

10 Figure 1 represents a vertical sectional view of a water tube boiler, embodying our invention, on line $y-y$ Fig. 2. Fig. 2 represents a section on line $x-x$ Fig. 1, certain parts being omitted for sake of clearness of 15 illustration. Fig. 3 represents a sectional view showing another embodiment of our invention, wherein three baffle plates are employed. Fig. 4 represents a sectional view of another embodiment of our invention 20 wherein four baffle plates are employed. Fig. 5 represents a transverse section of one of the water drums, showing the stiffening plates therein. Fig. 6 represents a section on line $z-z$, Fig. 5.

25 Similar numerals of reference indicate corresponding parts in the figures.

Referring to the drawings, 1 and 2 designate lower water drums which are supported upon a suitable boiler setting or brick-work 30 3 and 4 respectively, within which is contained the grate 5. 6 designates a steam drum which is of relatively large diameter and is supported in any suitable manner, said steam drum being connected to the lower 35 water drums by the lower nests of preferably curved water tubes 7 and 8. 9 and 10 designate upper nests of preferably curved water tubes common to said water drums 1 and 2 and said steam drum, the spaces intermediate said curved nests of water tubes being 40 occupied by nests of preferably straight water tubes 11 and 12.

13 and 14 designate diverging baffle plates which are supported in proximity to the 45 nests of straight tubes 11 and 12 respectively, in any suitable manner, it being apparent that said diverging or inclined baffle plates 13 and 14 may, if desired, be located at any suitable points intermediate the nests 50 of curved water tubes 7 and 8 and 9 and 10 respectively, without departing from the spirit of our invention.

15 and 16 designate lower inclined baffle plates which extend respectively in an upward direction from the lower inner portions of the water drums 1 and 2, said baffle plates 15 and 16 causing the products of combustion, after being temporarily pocketed in the upper secondary combustion chamber 17, to impinge upon the bottom of the steam drum 6 and the upper ends of the lower nests of curved tubes 7 and 8, as seen in Fig. 1, said products of combustion passing thence around the straight tubes 11 and 65 12 and thence over the lower edges of the

upper diverging baffle plates 13 and 14 through the flues 18 to the stack 19.

20 and 21 designate circulating pipes, which connect the lower portion of the interior of the steam drum 6 with the water 70 drums 1 and 2.

In the other embodiment of our invention seen in Fig. 3, we employ, if desired, three sets of baffle plates as 22, 23 and 24, the baffle plates 22 extending downwardly from the steam 75 drum 6 while the baffle plates 23 extend upwardly from the lower water drums, as 1 and 2, while the upper baffle plates 24 extend downwardly from the steam drum 6, so that a circuitous passage of the products of combustion is formed between said baffle plates 22, 23 and 24, as will be apparent to those skilled in the art.

In the construction illustrated in Fig. 3 and above described, the baffle plates 22 will 85 direct the hot gases and products of combustion first to the inner nest of tubes to cause the water to ascend, resulting in descent in the outer nests of tubes, which are exposed to the less heated gases.

In the construction seen in Fig. 4, we employ four baffle plates on each side of the furnace as 25, 26, 27 and 28, the baffle plates 26 and 28 extending upwardly from the lower water drums 1 and 2, while the upper 95 baffle plates 25 and 27 extend downwardly from the steam drum 6 so that the products of combustion are retained for a still longer period in proximity to the water tubes, as will be apparent to those skilled in the art. 100

It will further be seen that in our novel construction, we have elevated the side drums 1 and 2 to a considerable extent above the grate so that the secondary combustion chamber 17 is created, whereby a 105 much more extended grate surface is obtained than is obtained by the usual arrangement, where the grate is about on a line with the centers of the side drums. Attention is also called to the fact that in our novel construction, by the employment of the pair of water drums and the central enlarged steam drum, with nests of combined curved and straight tubes, the central drum is of a size to permit the withdrawal therein 110 of either the straight or curved tubes, as circumstances require, and while straight tubes have been used, no provision has ever been made for the use of nests of combined straight and curved water tubes in conjunction with our novel construction and collocation of baffle plates which is of great 115 importance and a decided improvement.

In most boilers, as heretofore constructed, 120 when it is desired to remove a defective tube or permit the application of a new or perfect one, it has generally been necessary to provide a construction of boiler having either a series of openings, in the opposite side of the drum, through which the tubes 125 130

may be withdrawn, or resort to a difficult and expensive arrangement of tubes installed so they can be drawn in the lengthwise direction of the drum, or to provide a 5 drum of abnormally large size. In providing holes through which the tubes can be removed, the drum is obviously weakened and the additional openings increase the liability of leaks. If the tubes are arranged 10 to draw in the lengthwise direction of the drum it necessitates curving the tubes and drilling the tube holes on an angle which is difficult and adds greatly to the cost of construction. If the drum is made large 15 enough to draw straight tubes into the drum its size is ordinarily prohibitive in boilers of this general type. In curing these serious defects, we make the tubes both curved and straight so that they will 20 occupy a position across the diameter of the drum when they are withdrawn, and provide a central drum of such diameter that it will permit of sufficient space to allow the curved and straight tubes to be pushed or 25 withdrawn entirely into said enlarged central drum, from whence they can be easily removed through a single manhole and new tubes inserted, which construction insures the minimum size of drum for removing 30 curved and straight tubes lying in a plane perpendicular to a plane passing through the center of the drum, which does not in the least increase the cost of the boiler, but retains the entire strength and durability 35 of the structure.

We have provided a boiler of increased economy and efficiency by our novel arrangement of baffle plates, that cause the gases of combustion to be temporarily 40 pocketed near the upper portion of the lower tube nests in the secondary combustion chamber 17, which provides for the mixing of the gases of combustion again after they have passed from the primary 45 combustion chamber near the grate to said secondary combustion chamber 17, thereby insuring complete combustion before the gases finally pass into the stack. The baffling causes the gases to be temporarily re- 50 tained in the secondary combustion chamber in proximity to the upper ends of the lower tubes before they are discharged to the smoke stack, which insures an increased efficiency for the boiler.

55 From the foregoing, it will be seen that we have provided an improved boiler which facilitates the securing in position of a large number of tubes in a vertical row, thus providing for our novel arrangement of baffling and thoroughly utilizing the heat 60 of the products of combustion as they pass between the tubes, while at the same time, the large steam drum increases the water and steam containing capacity of the boiler 65 reducing to a minimum the dangers and ac-

cidents resulting from low water and small water capacity and we have in addition provided a secondary combustion chamber 17 in which the gases of combustion are thoroughly commingled before passing to the 70 upper or outer nests of boiler tubes where the heat is finally extracted.

In all the embodiments of our invention it will be apparent that the number of nests of straight and curved tubes may be increased or diminished according to requirements and the outer nests of tubes may be inclosed in a suitable setting, as 29. It will be further apparent that in order to secure best results and to enable the replacement of 75 a leaking tube to be readily effected, as will be understood from the dotted lines in the steam drum of Fig. 1, we preferably construct the lower water drums with a convex tube sheet 30 attached to a somewhat similar 80 shaped outer curved sheet or member 31 so that said lower water drums 1 and 2 are substantially elliptical in cross section, as will be best understood from Fig. 5. It is essential that this shape in cross section of 85 said lower water drums 1 and 2 be substantially maintained under all conditions, and since said lower drums are large we attach to the inner surface of the outer sheets 31 a series of transversely arranged stiffening 90 plates 32, which are best seen in Figs. 5 and 6, said plates holding the lower or outer sheet 31 to its designed shape and preventing the lower drum from tending after use to 95 assume a circular shape due to the internal 100 pressure. This is an important feature of our novel construction, since said lower drums are large and we have found from practical use that they cannot be safely built without a provision of this character, and 105 it is possible to install these stiffening plates only in drums of large size, inasmuch as they cut off the access to the drums to such an extent that they cannot be installed in small drums. It will of course be apparent that 110 the general contour and design of these stiffening plates may be varied without departing from the spirit of our invention. By the employment of the large steam and 115 water drums and the wide nests of water tubes collocated in substantially the manner described, it is possible to install our novel arrangement of baffle plates and, at the same time, obtain sufficient area between said baffle plates for the gases of combustion to be 120 utilized to the fullest extent.

We preferably employ, in conjunction with the transversely arranged stiffening plates 32, a series of straight stiffening bars 34, which are secured to the ends of the 125 curved stiffening plates 32 in any approved or suitable manner, it being apparent that the precise form of these stiffening or reinforcing devices may be varied, if desired, as will be apparent to those skilled in this art. 130

We have found from practical experiments that our novel construction of boiler, while carrying twice or three times the amount of water which the water tube boilers now on the market carry, provides water area for the disengagement of steam from the surface of the water, approximately twice that of other water tube boilers with which we are familiar, and, in addition, we have found from practical experiments, that no water is carried up into steam, so that it is unnecessary to employ a steam separator in connection with our new boiler. Water tube boilers of ordinary construction under a heavy fire are liable to prime and carry water over to the steam main, whereas such objection is obviated in our construction, since only dry steam is generated under all conditions. The feed pump can be set in the morning and run all day without requiring attention from the operator even under considerable variation in load, due to ordinary working conditions. A water tube boiler constructed in accordance with our invention and the present system of baffling presents no pockets for the deposit of dust on the tubes or corners, which is an objectionable feature, and causes water tubes to burn out. Our novel boiler weighs much less than a Scotch boiler of equal capacity, and is especially adapted for use on ships, power stations or other plants requiring large boiler power in small space. In our novel construction of baffling, the arrangement of baffles allows sufficient space to permit of the gases supplying the dead points with heat, but there is no excess of space to allow the waste gases to heat the stack or to allow CO passing to the uptake before the air admitted above the fire has had opportunity to combine with this gas and burn.

It will now be apparent that we have devised a novel and useful construction of a steam boiler, which embodies the features of advantage enumerated as desirable in the statement of the invention and the above description, and while we have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described our invention what we claim as new and desire to secure by Letters Patent, is:—

1. In a water tube boiler, an upper steam drum, lower water drums, nests of tubes connecting the steam and water drums, a set of baffle plates extending from the steam drum toward the water drums and located near the lower portion of the tube nests, whereby an opening is provided between the end of

the baffle plates and the water drums for the admission of the hot gases to the tube nests, a second set of baffle plates located in the tube nests and extending from the water drums toward the steam drum, whereby an opening is provided between the ends of the baffle plates and the steam drum for the passage of the hot gases, and a third set of baffle plates extending from the steam drum toward the water drums and located still higher in the tube nests, whereby an opening is provided between the ends of the latter baffle plates and the water drums for the passage of the hot gases.

2. In a water tube boiler, an upper steam drum, lower water drums, nests of tubes connecting the steam and water drums, a set of baffle plates extending from the steam drum toward the water drums and located near the lower portion of the tube nests, whereby an opening is provided between the end of the baffle plates and the water drums for the admission of the hot gases to the tube nests, a second set of baffle plates located in the tube nests and extending from the water drums toward the steam drum, whereby an opening is provided between the ends of the baffle plates and the steam drum for the passage of the hot gases, and a third set of baffle plates extending from the steam drum toward the water drums and located still higher in the tube nests, whereby an opening is provided between the ends of the latter baffle plates and the water drums for the passage of the hot gases, in combination with a series of internal stiffening devices secured within said water drums to their outer sheets for reinforcing and stiffening said water drums, so as to prevent their distortion in use.

3. In a steam boiler, an upper steam drum, side water drums at a lower level, a plurality of nests of water tubes extending downwardly from said steam drum to said lower water drums, the upper and lower nests of said water tubes being curved in opposite directions, upper baffle plates located above said lower nests of tubes, said upper baffle plates extending in diverging directions downwardly from said steam drum toward said water drums, and lower baffle plates, the latter being inclined and converged upwardly and extending from the inner portion of said side water drums toward said steam drum, whereby an upper secondary combustion chamber is formed in proximity to the junction of the inner water tubes to said steam drum.

4. In a steam boiler, an upper central steam drum, side water drums arranged at a lower level, a plurality of nests of water tubes common to said central steam drums and each of said side drums, upper diverging baffle plates arranged within said water tubes and extending downwardly from said

steam drums toward said water drums, and lower converging baffle plates extending from said lower water drums toward said steam drum.

5. In a steam boiler, an upper steam drum, side water drums at a lower level, a plurality of nests of water tubes extending downwardly from said steam drum to said lower water drums, the upper nests of said tubes being curved in a convex direction outwardly, and the lower nests of said water tubes being curved inwardly toward the furnace in an opposite direction to said first mentioned tubes, said lower water drums being substantially elliptical in shape in cross section, and provided with a convex 70 tube sheet with which said tubes engage, the outer sheets of said water drums being also convex, and a series of internal, transverse stiffening devices secured within said water drums to said outer sheets for reinforcing and stiffening the latter, so as to prevent said water drums changing shape. 75

6. In a steam boiler, an upper steam drum, side water drums arranged at a lower level, a plurality of nests of water tubes extending downwardly from said steam drum toward said water drums, in combination with lower baffle plates, the latter being inclined and converged upwardly and extending from the lower portion of said side water drums toward said steam drum, whereby an upper secondary combustion 80 chamber is formed in proximity to the junction of the inner water tubes to said drum. 85

7. In a steam boiler, an upper central steam drum, side water drums arranged at a lower lever, a plurality of nests of water tubes common to said central steam drum and each of said side drums, upper inclined baffle plates arranged within said nests of water tubes and extending downwardly from said steam drum toward said water drums, and lower baffle plates extending upwardly from said lower water drums below said first mentioned baffle plates toward said steam drums, whereby a secondary combustion 90 chamber is created in proximity to the junction of the lower nests of water tubes with said steam drum. 95

8. In a steam boiler, a grate, a boiler setting extending a considerable distance above each side of said grate, water drums mounted upon said boiler setting on each side of said grate and above the latter, lower nests of curved water tubes extending from the lower portions of said water drums to the lower portion of said steam drum, upper nests of curved tubes extending from the upper portion of said water drum to said steam drum, intermediate nests of straight tubes 11 and 12 extending from said water 100 drums to said steam drum, upper baffle plates located intermediately of said curved nests of water tubes and diverging downwardly, and lower baffle plates extending upwardly from said water drums toward said steam drum, whereby a secondary combustion chamber is created in proximity to the junction of the upper ends of said lower nests of water tubes with said steam drum. 105

9. In a water tube boiler, an upper steam drum, side water drums arranged at a lower level, a plurality of nests of water tubes extending downwardly from said steam drum to said water drums, the upper nests of said water tubes being curved in a convex direction outwardly, and the lower nests of said water tubes being curved inwardly toward the furnace in an opposite direction to said first mentioned tubes, said lower water drums being substantially elliptical in shape in cross section, and provided with a convex 110 tube sheet with which said tubes engage, the outer sheets of said water drums being also convex, and a series of internal, transverse stiffening devices secured within said water drums to their outer sheets for reinforcing and stiffening said water drums, so as to prevent their assuming a cylindrical shape. 115

10. In a water tube boiler, an upper steam drum, side water drums arranged at a lower level, a plurality of nests of water tubes extending downwardly from said steam drum to said water drums, the upper nests of said water tubes being curved in a convex direction outwardly, and the lower nests of said water tubes being curved inwardly toward the furnace in an opposite direction to said first mentioned tubes, said lower water drums being substantially elliptical in shape in cross section, and provided with a convex tube sheet with which said tubes engage, the outer sheets of said water drums being also convex, and a series of internal, transverse stiffening devices within said water drums and secured to the outer sheets thereof for reinforcing and stiffening the latter, so as to prevent their assuming a cylindrical shape, in combination with baffle plates located in the spaces between each of said upper and lower nests of tubes, said baffle plates diverging downwardly from said steam drums toward said water drums. 120

11. In a water tube boiler, an upper steam drum, side water drums arranged at a lower level, a plurality of nests of water tubes extending downwardly from said steam drum to said water drums, the upper nests of said water tubes being curved in a convex direction outwardly, and the lower nests of said water tubes being curved inwardly toward the furnace in an opposite direction to said first mentioned tubes, said lower water drums being substantially elliptical in shape in cross section, and provided with a convex tube sheet with which said tubes engage, the outer sheets of said water drums being also convex, and a series of internal, transverse stiffening devices secured within said water drums to their outer sheets for reinforcing and stiffening said water drums, so as to prevent their assuming a cylindrical shape. 125

12. In a water tube boiler, an upper steam drum, side water drums arranged at a lower level, a plurality of nests of water tubes extending downwardly from said steam drum to said water drums, the upper nests of said water tubes being curved in a convex direction outwardly, and the lower nests of said water tubes being curved inwardly toward the furnace in an opposite direction to said first mentioned tubes, said lower water drums being substantially elliptical in shape in cross section, and provided with a convex tube sheet with which said tubes engage, the outer sheets of said water drums being also convex, and a series of internal, transverse stiffening devices secured within said water drums to their outer sheets for reinforcing and stiffening said water drums, so as to prevent their assuming a cylindrical shape. 130

6

vex direction outwardly, and the lower nests of said water tubes being curved inwardly toward the furnace in an opposite direction to said first-mentioned tubes, nests 5 of straight tubes located intermediately of said curved tubes, said lower water drums being substantially elliptical in shape in cross section, and a series of internal, transverse stiffening devices for reinforcing and 10 stiffening said water drums, so as to prevent their assuming a cylindrical shape, in combination with baffle plates located in the space between each of said upper and lower nests of tubes, said baffle plates diverging 15 downwardly from said steam drums toward said water drums.

12. In a steam boiler, a steam drum, side water drums at a lower level than said drum, diverging tubes connecting said 20 steam drum and side water drums, and oblique baffle plates extending alternately from said drums and between the nests of tubes to form diverging and tortuous paths for the products of combustion through said 25 tube-nests, in combination with a series of internal stiffening devices secured within said water drums to the outer sheets thereof for reinforcing and stiffening said water drums, so as to prevent their distortion in 30 use.

13. In a steam boiler, a steam drum, water drums arranged below and to the sides of said steam drum, tubes diverging from said steam drum to said water drums, and oblique baffle-plates supported in the nests of diverging tubes and alternately from said drums to form tortuous passages through the nests of tubes, in combination with a series of internal stiffening devices secured 40 within said water drums to the outer sheets thereof for reinforcing and stiffening said water drums, so as to prevent their distortion in use.

14. In a steam boiler, a steam drum, water-drums arranged below and lateral to said drum, nests of diverging tubes extending from said steam drum to said water

drums, baffle-plates extending to cover the lower portions of the lower nests of tubes, and baffle plates arranged between the nests 50 of tubes to form tortuous passages, in combination with a series of internal stiffening devices secured within said water drums to the outer sheets thereof for reinforcing and stiffening said water drums, so as to prevent their distortion in use. 55

15. In a steam boiler, a steam drum, water-drums arranged below and lateral to said drum, nests of tubes diverging from the steam-drum to the water drums, and 60 baffle-plates alternately extending from said drums for a part of the space between them and partly separating said nests to form tortuous passages through the same, in combination with a series of internal stiffening 65 devices secured within said water drums to the outer sheets thereof for reinforcing and stiffening said water drums, so as to prevent their distortion in use.

16. In a steam boiler, a steam drum, water drums arranged below and lateral to said drum, tubes diverging from the steam drum to span the space between the same and the water drums in longitudinally extending nests, and inclined baffle plates arranged in juxtaposition to and intermediate 75 such nests to form tortuous passages through the same, in combination with a series of internal stiffening devices secured within said water drums to the outer sheets 80 thereof for reinforcing and stiffening said water drums, so as to prevent their distortion in use.

17. In a steam boiler, a water drum oblong in cross-section, arcuate stiffening 85 plates secured to the inner side of the wall of the drum, and brace bars extending across between the ends of said plates to form chords to the arcs of the latter.
